UNITED STATES PATENT OFFICE.

ARTHUR OLLENDORFF, OF BRESLAU, GERMANY.

MANUFACTURE OF PLATES FOR ARTIFICIAL TEETH.

No. 829,997.

Specification of Letters Patent.

Patented Sept. 4, 1906.

Application filed February 28, 1905. Serial No. 247,819.

To all whom it may concern:

Be it known that I, ARTHUR OLLENDORFF, a subject of the King of Prussia, residing at Breslau, in Germany, have invented certain new and useful Improvements in the Manufacture of Plates for Artificial Teeth, of which the following is a specification.

This invention relates to improvements in the manufacture of plates for artificial teeth, reference being made to the annexed drawings, in which—

Figure 1 is a plan, and Figs. 2 and 3 sections, illustrative of the improved method.

It is known that metallic plates for artificial teeth have over those of caoutchouc the advantages of greater convenience and durability, but the manufacture of such plates is at present invariably effected by stamping them out of metal plates, the teeth and 15 clamps being subsequently soldered on. The reason for the adoption of this method of manufacture lies in the fact that the methods which have hitherto been known for casting metallic plates are still more inconvenient 20 than that of stamping, while they do not obviate the necessity for soldering on the teeth and clamps. To these causes is due that metallic plates have not hitherto entirely superseded those of caoutchouc, notwithstanding 25 the advantages of the former. United States Patent No. 633,222 relates, for instance, to a method for casting aluminium plates for artificial teeth. According to the method described in the specification of this 30 patent a wax model or pattern is placed, for the purpose of producing the mold, in a two-part flask containing fireproof material, the flask being thereupon opened and washed out with hot water for the purpose of 35 removing the wax. In order to remove such traces of wax as remain in the mold after the washing process, the flask is thereupon placed in a suitable furnace, in which the 40 wax is burned out.

According to the present invention, plates for artificial teeth are produced by casting with wax models in a manner similar to that adopted for casting delicate metal ornaments and the like. This method has, over 45 that described in the patent referred to, the advantage that the washing out of the wax is rendered unnecessary, the said wax being entirely removed by a burning process. The improved method also has the advantage 50 that it allows of dispensing with flasks made in parts, the use of such flasks being incon-

venient, inasmuch as the parts cannot be readjusted in exactly the original position after they have been separated for the purpose of washing out the wax. The flasks used according to the present invention allow of producing molds for the production of which flasks consisting of more than two parts would be required according to the older method, and the cast can therefore be 60 made to include the necessary clamps and to constitute not only the plate, but the complete outfit required, which may consist of gold, silver, or other metal. This was hitherto not 65 practicable.

According to the present invention an impression of the patient's gums and mouth is made in the usual way and with the known material. From this impression a model *a* is thereupon made in the known manner with 70 the aid of a suitable mixture of gypsum and fireproof material, the said model being adapted to serve as part of the mold. The plate *b* is thereupon modeled in wax upon the gypsum model, and the wax model resulting therefrom, with or without the gypsum model, is embedded in a mixture of gypsum and fireproof material *c*, placed in a flask of clay *d* or the like. The teeth *e* need not be provided with a protective plate. Gates of 75 colophony or wax for the molten metal are made in the mold in the usual manner, and air-holes are provided, if required. When the gypsum, with its admixture of fireproof material, has become dry, it is subjected to 80 such a degree of heat in the flask that the wax is by this means completely evaporated and the mold for casting produced. During the casting of the plate the teeth are very liable to become cracked. It has been found 85 that in order to prevent this the mold with the teeth therein must be maintained for a considerable time at red heat, but at a temperature below the melting-point of the metal used. Care must be taken not to heat the 90 mold for too long or too short a period or at a lower or higher temperature—for instance, at the temperature at which the metal melts—since this has been found in almost all cases to result in the cracking of the teeth. For 95 this reason no satisfactory result has been obtained by using the same furnace for heating the mold and fusing the metal. A separate furnace is therefore preferably used for the latter purpose. It has also been found that 100 to prevent the cracking of the teeth the mold must not be removed from the heating— 105

furnace for the purpose of making the cast—that is to say, the cast must be made in the heating-furnace itself. This may be due to the fact that the mold becomes slightly 5 cooled immediately on its removal from the heating-furnace and that the reduction of temperature causes the teeth to crack. The method of manufacture above described is more simple and cheap than any which has 10 hitherto been devised. Any suitable metal or alloy can be used for making the plates. The method can also be conveniently combined with the use of caoutchouc, enamel, and 15 gold and employed for making single teeth, crowns, and bridges.

What I claim as my invention, and desire to secure by Letters Patent of the United States, is—

1. A method for the manufacture of metallic plates for artificial teeth consisting in producing an impression of the mouth, making from said impression a plaster model, modeling the plate in wax upon said plaster model, embedding the wax model in fireproof material 20 to form a mold, embedding the teeth in the wax model and mold, heating the mold 25 in a furnace by which the wax is completely

evaporated and casting the plate in said mold, substantially as described.

2. A method for the manufacture of metallic plates for artificial teeth consisting in producing an impression of the mouth, making from said impression a model consisting of a mixture of gypsum and fireproof material, modeling the plate in wax upon said gypsum 30 model, embedding the wax model with the gypsum model in a mixture of gypsum and fireproof material within a flask to form a mold, embedding the teeth in the wax model and mold, allowing the mold to dry, heating 35 the mold and flask in a furnace to a temperature sufficient to completely evaporate the wax casting the plate in the mold in said furnace and maintaining the mold for a considerable time at a red heat but below the melting 40 temperature of the metal substantially as described.

In witness whereof I have signed this specification in the presence of two witnesses.

ARTHUR OLLENDORFF.
